US00D729249S

(12) **United States Design Patent**
Sun et al.

(10) **Patent No.:** US D729,249 S
(45) **Date of Patent:** ** May 12, 2015

(54) **MEMORY ACCESS DEVICE**

- (71) Applicant: **Silicon Power Computer & Communications Inc.**, Taipei (TW)
- (72) Inventors: **Po-Ming Sun**, Taipei (TW); **Chao-Hung Huang**, Taipei (TW); **Chen-Yu Wang**, Taipei (TW); **Hung-Sheng Huang**, Taipei (TW)
- (73) Assignee: **Silicon Power Computer & Communications Inc.**, Taipei (TW)
- (**) Term: **14 Years**
- (21) Appl. No.: **29/494,606**
- (22) Filed: **Jun. 23, 2014**

(30) **Foreign Application Priority Data**

Dec. 25, 2013 (TW) 102308369

FIG. 1 is a perspective view of a memory access device according to the present design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Broken lines and entirely unshaded portions contained within broken line are not claimed.
